UNITED STATES PATENT OFFICE.

ISIDOR KITSEE, OF PHILADELPHIA, PENNSYLVANIA.

ELECTRIC SWITCH OR CUT-OUT.

No. 876,809

Specification of Letters Patent.

Patented Jan. 14, 1908.

Application filed October 14, 1906. Serial No. 282,816.

To all whom it may concern:

Be it known that I, ISIDOR KITSEE, of the city and county of Philadelphia and State of Pennsylvania, have invented certain new and useful Improvements in Electric Switches or Cut-Outs, of which the following is a specification.

My invention relates to an improvement in electric switches or cut-outs and has more special reference to such devices where heavy currents are used, no matter if these currents are uni-directive or not.

Referring to the drawing: Figure 1 is a side elevation of the device, embodying my invention, partially in section. Fig. 2 is a top plan view of the device embodying my invention.

A is a receptacle made of a non-conducting material, such for instance as glass, porcelain, or what is preferred, of wood, put together without the aid of metallic contrivances, such as nails etc., only the ends being secured by heavy braces. This latter construction is clearly shown in the drawing.

1 and 2 are insulated conductors carrying the current. The conductor 2 is in electrical contact with the conducting piece 3. This conducting piece is in electrical contact with the stationary conducting device, here shown 30 as a tube B. All these connections are preferably made of metal, such as copper. In the metallic tube B is placed the spring D and the carbon C. The spring tends to press the carbon partially out of the tube. The wire 1 is connected with the contact 4 and this contact 4 is in electrical connection with the cable F¹ wound around the drum or reel F. This reel is carried by the movable truck E. The terminal of the cable F¹ is in electrical connection with the contact B¹ consisting as does the contact B, of a metallic tube and having inserted therein the spring D¹ and the carbon C¹. The vessel or receptacle A is preferably filled with a non-conducting liquid, such as oil.

The receptacle A is pivoted in the center, as illustrated, with the aid of the holder a at a¹ to the support a² in a manner so that it may be rocked or swung from one side to the other, and to facilitate this rocking or swinging motion the receptacle is further provided with the lever a³.

It is supposed that, as illustrated in the drawing, the stationary contact B and the movable contact B¹ are out of connection and the receptacle is tilted so that its right-hand

end rests on the floor or under-support. In this position the weight of the carriage or truck E with its contact B¹ is sufficient to keep this receptacle in its tilted position till an outside force is brought to bear on it for the purpose of altering such position. This outside force may be manually or electro-magnetically applied, but as said above, I prefer for simplicity's sake, to have a lever whereby the operator can easily tilt the receptacle to one side or the other. Now, as long as the receptacle remains in the position as illustrated, the two contacts being apart from each other and the wires 1 and 2 connected to the power circuit, this power circuit is effectually broken. Should now the person in charge operate the lever a³ so as to cause the left-hand end of the receptacle to move downwards and the right-hand end to move upwards, then the carriage with its contact will travel towards and in contact with the stationary contact B, but first of all the compressible carbons C and C¹ will be contacted and the force of the moving vehicle will drive these two carbons inside of their respective tubes and will thereby bring the terminals of both the metallic tubes in contact with each other, effectually closing the circuit. The weight of the traveling carriage will now keep the left hand side of the receptacle downwards till another operation reverses the action.

For clearer understanding, I designate the end of the receptacle containing the stationary contact B by the numeral 5 and the opposite end of the receptacle by the numeral 6. To make a circuit with this my device it is therefore only necessary for the attendant to move the lever in a manner so that the end 5 shall rest on the under-support or floor and the end 6 shall be raised upward, and to break circuit it is only necessary to move the lever a³ in a manner so that the end 6 shall come to rest on the floor or under-support and the end 5 shall be raised upwards.

It is obvious that the receptacle shall be provided with means so that the carriage may travel easily and not swerve to the right or left but keep its center position, and I have shown such means in the drawing as additional tracks K; these tracks may be made of wood or any other suitable substance.

It is not one of the least advantages of this device that the entire volume of oil is brought in motion by the making as well as the breaking of the circuit.

Having now described my invention, what I claim as new and desire to secure by Letters Patent is:—

1. In an electric switch, a receptacle, a support upon which said receptacle is tiltably mounted, means to tilt said receptacle, a stationary contact arranged within said receptacle, a movable contact also arranged in said receptacle, a carriage upon which said movable contact is mounted, and circuit connections for said contacts.
2. In an electric switch, a receptacle, a support upon which said receptacle is tiltably mounted, a stationary contact arranged within said receptacle, a movable contact also arranged in said receptacle, a carriage upon which said movable contact is mounted, conductors included in said contact and normally projecting therefrom, circuit connections for said conductors, and a non-conducting fluid within the receptacle to cover the meeting points of the contacts.
3. In an electric switch, a tilttable receptacle, two metallic contacts arranged in said receptacle and each provided with a carbon normally projecting in advance thereof and adapted to be operated in alinement with said contacts, a carriage arranged within said receptacle and upon which one of said contacts is mounted, whereby the same is moved towards and away from the other contacts, and means for causing such movement of said carriage.
4. A device of the class described consisting of a retainer or receptacle adapted to be tilted to one side or the other, two contacts in said receptacle, at least one of said contacts carried by a movable carriage, means to connect the terminal of a circuit to said contacts, and means to tilt said receptacle.
5. Means to connect and to break a current-carrying circuit, said means embracing a receptacle adapted to be tilted, said receptacle containing the terminals of said circuit, at least one of said terminals being carried by a movable carriage.
6. In an electric switch, a receptacle tiltably mounted, a fixed contact arranged therein, a carbon arranged within said fixed contact, a spring also arranged within said fixed contact and normally projecting said carbon beyond said fixed contact, a movable contact also arranged within the receptacle, a carbon arranged therein, a spring also arranged within the movable contact and adapted to normally project the carbon of said contact therefrom, a carriage upon which said movable contact is mounted, whereby said movable contact is carried towards and away from the fixed contact, and circuit connections for said contacts.
7. In an electric switch, a receptacle tiltably mounted, a fixed contact arranged therein, a carbon arranged within said fixed contact, a spring also arranged within said fixed contact and normally projecting said carbon beyond said fixed contact, a movable contact also arranged within the receptacle, a carbon arranged therein, a spring also arranged within the movable contact and adapted to normally project the carbon of said contact therefrom, a carriage upon which said movable contact is mounted, whereby said movable contact is carried towards and away from the fixed contact, circuit connections for said contacts, and a non-conducting fluid arranged within the receptacle and adapted to cover the meeting points of the contacts.
8. In an electric switch, a support, a stationary contact carried by said support, a movable contact also carried by said support, a carriage upon which said movable contact is mounted, and circuit connections for said contacts.

In testimony whereof I affix my signature in presence of two witnesses.

ISIDOR KITSEE.
